CLAIM

The ornamental design for a seed starter tray unit, as shown and described.

DESCRIPTION

FIG. 1 is a front perspective view thereof;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view showing in a closed state; and, FIG. 9 is an enlarged view of portion "9" in FIG. 1.

The portions of the seed starter tray unit shown in broken line form no part of the claimed design.
